(57) **CLAIM**

The ornamental design for a magnetic grasping device, as shown and described.

DESCRIPTION

FIG. 1 is a perspective view of a magnetic grasping device design showing my new design.

FIG. 2 is a perspective view of a magnetic grasping device, showing in an extended state.

FIG. 3 is a front view of a magnetic grasping device.

FIG. 4 is a rear view of a magnetic grasping device.

FIG. 5 is a left side view of a magnetic grasping device.

FIG. 6 is a right side view of a magnetic grasping device.

FIG. 7 is a top view of a magnetic grasping device; and,

FIG. 8 is a bottom view of a magnetic grasping device. Any shading and cross-hatching are not features of the design but are utilized to illustrate the surface contours of the magnetic grasping device design in the drawings.
